Martin Jachimow

UNITED STATES PATENT OFFICE

MAURICE J. WOHL, OF LONG ISLAND CITY, NEW YORK

ONE-HAND ARC LAMP

Application filed November 16, 1925. Serial No. 69,538.

This invention relates to electric arc-lamps of the hand operated type and particularly to lamps used for photographic and medical purposes.

5 It is the object of the present invention to provide a lamp which is extremely light in weight so that it may be carried and operated by one hand.

10 It is another object of this invention to provide a lamp which, although its electrodes are fed by hand, requires no careful adjustment by the operator to produce or to hold an arc.

15 It is a further object of the invention to provide a relatively small lamp which holds an arc at a fixed point and therefore may be used as a focussing lamp in connection with a lens or mirror.

20 With these and other objects in view, the invention consists in a novel arrangement of parts and details of construction hereinafter fully described and finally pointed out in the claims.

25 In the drawing which forms a part of this specification

Fig. 1 is a side elevation of my hand lamp.

Fig. 2 is a front elevation of the lamp in the direction of arrows 2—2 of Fig. 1.

30 Fig. 3 is a top plan of Fig. 1, partly in section, on line 3—3 of Fig. 1.

Fig. 4 is a detail vertical section through the arc-former barrel 21 on line 4—4 of Fig. 2.

35 Fig. 5 is a sectional plan on line 5—5 of Fig. 4.

Referring to Fig. 1 of the drawing, 11 represents a substantially V shaped bar arranged horizontally which holds by means of a flat portion at the apex and by bolt 29 a concave mirror 12. While the inclined parts of bar 11 are resilient to form co-operating springs, it is not essential that the vertical portion between them is resilient. Near mirror 12 the wide spaces of bars 11 are horizontal transversely, they are twisted at 11^a, so that the forward parts 11^b of the two arms are in the same vertical plane. At their front ends each of the diverging arms 11^b holds a carbon holder bracket 13, insulated from the arms 11^b. These arms are each provided with a

terminal binding post 14 and with a carbon holder 15 which in turn hold the carbon electrodes 16 and 17. These electrodes are held perpendicular to arms 11^b which gives them a considerable inclination with the horizontal axis A—A of the mirror 12 and the whole lamp. To the middle portion of the upper arm 11^b, a short horizontal post 18 is pivotally fastened by means of a horizontal pivot 30. This post holds a vertical cylindrical rod 19 extending downwardly therefrom. The upper end of rod 19 is formed into a pivot 20 which turns in an aperture of post 18. To the middle portion of the lower arm 11^b, a cylindrical barrel 21 is rotatably fastened by 55 means of a pivot pin 22 about which it may rotate. The rod 19 passes through the axis of barrel 21 and carries below the same a stop collar 23 and at its lowest point a horizontal handle 24. Within the barrel 21 (see Fig. 4) 60 the rod 19 is encircled by a ring 25 which is made by winding a helical spring around this rod and joining the two ends of the spring to each other. While spring 25 tightly embraces rod 19 its circumference is free from 65 the side wall of barrel 21. The top 21^a of the barrel 21 carries a number of washers 26 of varying thicknesses suitably fastened thereto for increasing or decreasing the space between these washers and the bottom 21^b of the barrel. To bottom 21^b is also fastened a vertical rod 27 which reaches a distance below handle 24 and terminates at its lower end in a crescent shaped plate 28.

70 The operation of this lamp is as follows:

Assuming that the terminals 14 are connected to an electric circuit and the electrodes are separated far apart, which is accomplished by simply spreading the arms 11^b, the lamp is preferably held by placing the first finger of one hand under plate 28 and the second and third fingers upon handle 24 so that rod 19 passes between these fingers. By pressing the fingers against the handle 24 and plate 28 these elements approach each other, barrel 21 travels upward on rod 19 and electrodes 16 and 17 approach each other until they reach the axis A—A and form a contact, at their pointed ends, closing the circuit. The lifting of barrel 21 caused the 75 80 85 90 95 100

bottom plate 21^b to travel upward until it touched the lower face of coiled spring 25 and then to shift this spring upward on rod 19 until the movement is arrested by the touching of the two electrodes. If then the 5 manual pressure is released the spring 11 presses the two arms 11^b uniformly apart from axis A—A. The barrel 21 descends on rod 19 until the lowest washer 26 therein touches the upper face of coiled spring 25. 10 This distance of descent is equal to the distance between the bottom 21^b and spring 25 before the barrel was lifted. The force of spring 11 is insufficient to overcome the friction 15 of coil spring 25 on rod 19 and therefore this spring acts as a positive stop for the opening movement of arms 11^b. The two electrodes 16 and 17 being held by the arms 11^b have opened a distance above and below 20 axis A—A the length of which is fixed by the above described movement of washer 26 towards spring 25 and formed an arc thereby on the focal axis of mirror 12.

When the electrodes burn off and the arc 25 becomes too long the above described action is repeated and a new arc established on the focal axis of the same fixed length.

It is also possible to hold the arc at a shorter length than the standard distance fixed by 30 the space between 25 and 21^b, and to adjust it, by varying the hand pressure.

The collar 23 on rod 19 serves as a stop for barrel 21 to prevent an excessive separation of the electrodes.

35 The lamp may be placed on a suitable stand in several ways. If the crescent shaped plate is replaced by a flat plate or disk a stand is formed to place the lamp on a table. It may then be operated by simply pressing upon 40 handle 24. It may also easily be attached to a stand by means of bolt 29.

It is evident that in addition to the mirror 45 12 a focusing lens may be arranged in front of the electrodes on the focal axis for projection purposes and suitably connected to the mirror on bolt 29.

This lamp is particularly suited for physicians in the treatment of bacterial diseases on account of its lightness and easy operation. 50 It may be carried and operated by one hand and the arc formed and maintained at correct length without gauging or adjusting the same. It may be brought close to the patient and used in any desired direction.

55 This lamp is a very desirable one for photographic purposes, if attached to a stand as above described. The arc once established holds steady long enough for an exposure and can be restored to original length with 60 facility and without disturbing the exposure. In addition to these advantages the construction of the whole lamp is extremely simple and the number of its parts in comparison with similar devices is greatly reduced. It 65 can therefore be manufactured and sold for

a very reasonable price, making it possible for any practicing physician to treat the above named diseases without cumbersome and costly apparatus and in a more efficient manner.

70 It will be clear that such changes may be made in the general arrangement of the lamp and in the construction of the minor details thereof, as fall within the scope of the appended claims, without departure from the 75 spirit of invention.

Having thus described my invention, what I claim as new, and desire to secure by Letters Patent is:

1. In an arc lamp a frame consisting of 80 two arms joined to each other at one end and holding electrodes at their free ends, resilient means joining said arms to separate said arms simultaneously equal distances from a common axis, means slidably guided by said arms to move them quickly towards each other until said electrodes form a contact and means to form an arc between said electrodes operated by said resilient means.

2. An arc lamp consisting of a pair of arms 85 forming a V shaped frame, resilient means joined to both arms of said frame to separate said arms, electrodes at the free ends of said arms, means slidably connected to both arms to move said electrodes quickly a long distance to form a contact, and means to form an arc by releasing said sliding means a short distance.

3. In an arc lamp a pair of arms supporting 90 electrodes, resilient means to separate said electrodes, clutch operated means to form an arc of fixed length, a pair of sliding rods joining said arms forming common means for manual support of said lamp for quickly bringing said electrodes together and 95 for operating said arc forming means.

4. In a lamp a pair of electrodes, a supporting arm for each electrode, resilient means to spread said arms apart, a connecting rod fastened to one of said arms and slidably held on the second arm, a friction collar on said rod and a pair of stops on the second arm arranged on opposite sides of said collar to provide arc forming means for said lamp.

5. In a lamp a pair of electrodes, a supporting arm for each electrode, means for spreading said arms apart, means for forming an arc, means for supporting said lamp attached to one of said arms and means for operating said arc forming means attached 110 to the other arm, said arc forming means including a stop for fixing the length of arc and means to alter said fixed length.

6. In an arc lamp a pair of electrodes, a supporting arm for each electrode, means for spreading said arms apart, a rod connecting said arms pivotally held on one arm, a guide for said rod pivotally held on the other arm, means slidably held on said rod and operated by said guide to vary the position of 115 120 125 130

said arms and to form an arc between said electrodes.

7. In an arc lamp a pair of electrodes, a supporting arm for each electrode in symmetrical position to a common axis, means for moving said arms simultaneously equal distances towards and away from said axis, a rod connecting said arms arranged perpendicularly to said axis, and means on one of said arms in slidable engagement with said rod to form an arc between said electrodes on said axis.

8. In a lamp, a pair of electrodes, holders for said electrodes mounting them in arc forming relation to each other, an operating rod to effect movement of one electrode towards the other, a friction collar on said rod and a pair of stops arranged on opposite sides of said collar to provide arc forming means for said lamp.

9. In a lamp a pair of arc forming electrodes, holders for said electrodes mounting them in arc forming relation to each other, means to press said holders apart, an operating rod to effect movement of one electrode holder towards the other and friction means engaging said rod, a pair of stops on opposite sides of said friction means adapted to engage the same and to fix the length of the arc formed when the said rod is released.

10. In a lamp a pair of arc forming electrodes, arms holding said electrodes in angular relation to each other, means for normally separating said arms, operating means for pressing said arms together and friction means in engagement with said operating means and means co-operating with said friction means to limit the separation of said arms to strike an arc by the release of said pressure.

11. In an arc lamp a pair of electrodes, supporting arms mounting said electrodes in arc forming relation, spreading means to move said arms apart, a rod slidably connected to one of said arms to move the electrode held thereon to a contact by manual pressure, friction means engaging said rod and means co-operating with said friction means to limit said spreading movement to form an arc under action of said spreading means.

In testimony whereof, I have signed my name to this specification this 31st day of October, 1925.

MAURICE J. WOHL.
